UNITED STATES PATENT OFFICE.

WILLIAM C. GREGG, OF HACKENSACK, NEW JERSEY, ASSIGNOR TO THE GREGG COMPANY, LIMITED, OF NEWBURGH, NEW YORK, A CORPORATION OF NEW YORK.

CANE-SLING.

1,181,000.

Specification of Letters Patent.

Patented Apr. 25, 1916.

Application filed January 13, 1915. Serial No. 2,047.

To all whom it may concern:

Be it known that I, WILLIAM C. GREGG, a citizen of the United States, and a resident of the village of Hackensack, county 5 of Bergen, and State of New Jersey, (whose post-office address is Hackensack, New Jersey,) have invented a new and useful Improvement in Cane-Slings, which invention is fully set forth in the following specification.

10

Although this invention is intended primarily for holding bundles of sugar-cane and transporting the bundles as units, yet the invention can be applied to other articles as well.

One object of the invention is to provide a device which will conform to the varying and more or less circular contour of the bundles of sugar-cane or other articles.

20 Another object is to produce an improved device which is unfailing and certain in its operation, comparatively inexpensive to manufacture, simple to use, and durable during prolonged service from season to season.

25 The various features of construction and arrangement, and the resulting advantages, will be best understood by reference to the accompanying drawings which illustrate a preferred embodiment of the new sling.

30 In these drawings: Figure 1 is an end view of the bundle of sugar-cane held securely clamped and suspended by the new sling; Fig. 2 is a vertical section taken longitudinally through Fig. 1; Fig. 3 is a top view of the same; and Fig. 4 is a detail.

35 The block or frame consists of the two members 1 and 2, connected together by the pivot 3. Each member consists of two substantially flat sides or faces united by the 40 transverse web-portions, as seen in Figs. 2 and 3.

45 4 is a pulley journaled in the outer end of the member 1. The chain or rope 5 passes around this pulley and its free end is detachably connected to the outer end of member 2, as hereinafter described.

50 6 is a latch, located in member 1 and journaled upon the pivot 3.

55 7 is a spring interposed between a web-portion of member 1 and the latch 6. The arrangement is such that the spring causes the latch to clamp the chain against the pulley, so that although the chain can be drawn freely outward, past the latch, yet it cannot be drawn in the other direction.

If desired, this latch can be provided with a handle 8, by which it may be lifted manually out of the path of the chain, which latter can then travel freely in either direction.

60 In the outer end of the member 2 is pivoted the catch 9, shown as crescent-shaped to provide the nose 10 and the hook 11, for receiving ring 12 on the free end of the chain. In the same member 2 is pivoted the lock 13, having the handle 14. The parts are 65 so shaped and arranged that the nose 10 lies behind the lock 13 whose periphery prevents the catch being swung farther outwardly. But the lock is cut-away at 15 (see Fig. 4), so that when the handle 14 has been shifted 70 (to the right in Fig. 2) the nose 10 can pass out and the catch will release the ring 12 (and the end of the chain). A spring 16 is interposed between the web of member 2 and a projection 17 on the lock. This spring 75 normally holds the parts in the position indicated in Fig. 2.

80 The outline of member 1 is such as to cover and protect the pulley and all of the latch and its spring except the handle 8. In like manner the sides of member 2 cover and protect all of the lock 13 and its spring except the handle, and also the nose of the catch; but this member 2 is so shaped, and the catch so located, as to expose the hook 85 11. Preferably the end of this hook (when in normal position) extends almost to the lock, so as to prevent accidental escape of the ring 12.

90 The manner of using the sling will now be readily understood. The handle 14 having first been shifted so as to release the end of the chain, the chain is then either stretched out flat upon the ground, or laid across the wagon bed or cane-car; and then 95 the canes are piled lengthwise across the chains until a suitable bundle has been accumulated. Then the ends of the chain are drawn upward and the ring 12 engaged over the hook 11 of its catch 9 (the handle 100 14 and the hook being first shifted to permit this). And then the other end of the chain is drawn outward, around the pulley 4, until the bundle has been compressed as compactly as desired, meanwhile the latch 6 105 automatically coming into play to prevent the chain from being drawn backward. During this operation the pivot 3 permits the jointed block 1-2 to conform as nearly as may be to the contour of the bundle of 110

canes. The complete bundle may now be hoisted (as indicated in Fig. 1) or otherwise handled and transported. When it is desired to release the bundle, a pull upon handle 14 (to the right in Fig. 1) instantly and automatically releases the ring and its end of the chain, and the bundle is at once discharged from the sling.

The invention has been described with 10 great particularity of detail but only for the sake of clearness; and it is to be understood that the invention is not limited to the precise construction and arrangement of the parts.

15 It will also be understood that if desired there may be two or more chains, each provided with a similar arrangement of jointed members 1-2, each containing a pulley and its latch 6, as well as a catch 9 and its lock 13.

20 What is claimed is:

1. In a cane-sling, the combination of two members pivotally connected together, a cable-bearing-surface on one member with 25 a detent co-acting therewith and journaled on the pivot of said members, and a device carried by the other member for detachably securing the end of a cable.

2. In a cane-sling, the combination of two 30 members pivotally connected together and each comprising two substantially parallel flat faces united by web-portions for inclosing a separate interior compartment, a cable-bearing-surface within one of said compartments, a co-acting spring-pressed 35 detent journaled within that same compartment upon the pivot of said members, and a device carried by the other member for detachably securing the end of a cable.

40 3. In a cane-sling, the combination of two members pivotally connected together, each comprising two substantially parallel flat faces united by web-portions for inclosing an interior compartment, a cable-bearing- 45 surface and a co-acting detent located within one of said compartments, a hook pivotally located within the end of the other compartment and protruding therefrom, a catch for said hook pivotally journaled 50 within that second compartment, and a spring bearing against said catch and against a portion of the web of said compartment respectively.

45 4. In a cane-sling, the combination of a 55 frame having substantially flat sides connected by transverse web-portions, a second frame of similar construction, a pivot connecting the two frames together, a detent located within one of said frames and journaled upon said pivot to engage a cable 60 passing through that same frame, a spring

interposed between a portion of the web of said frame and said detent to force the latter against said cable to prevent it passing in reverse direction, a device journaled within 65 the other frame for detachably holding the end of said cable, and spring-actuated means within that second frame for normally holding said device in position to securely hold the cable.

70 5. In a cane-sling, the combination of a rope or chain, a member having two parts pivotally connected one to the other, one of said parts engaging said rope intermediate its ends and normally slidably thereon in 75 one direction only, a spring-pressed latch mounted on said pivotal connection to prevent sliding in the opposite direction, and means carried by the other of said parts for normally engaging one end of said rope to 80 form an adjustable loop.

6. In a cane-sling, the combination of a rope, a member having two parts pivotally connected one to the other, one of said parts engaging said rope intermediate its ends 85 and normally slidably thereon in one direction only, a spring-pressed latch mounted on said pivotal connection to prevent sliding in the opposite direction, spring-pressed means carried by the other of said parts 90 for normally engaging one end of said rope to form a loop, and additional means to release said engaging means at will.

7. In a cane-sling the combination of a rope, a block normally slidable thereon in 95 one direction, a latch to prevent sliding in the opposite direction, a second block carrying means for normally engaging one end of said rope to form a loop, means for releasing said engaging means, and a pivot 100 joining both of said blocks and providing a bearing for said latch.

8. In a cane-sling the combination of a rope, a clamp slidable thereon, a latch carried by said clamp and adapted to engage 105 said rope to prevent sliding except in one direction, and means to release said latch and permit sliding in the opposite direction at will, a second clamp carrying means for normally engaging one end of said rope, 110 additional means for releasing said engaging means, and a pivot connecting said clamps one to the other and providing a bearing for said latch.

In testimony whereof I have signed this 115 specification in the presence of two subscribing witnesses.

WILLIAM C. GREGG.
